Inventor

United States Patent Office.

CHARLES PARKER, OF MERIDEN, CONNECTICUT.

Design No. 3,443, dated April 6, 1869.

DESIGN FOR A TOBACCO-BOX.

The Schedule referred to in these Letters Patent and making part of the same.

To all whom it may concern:

Be it known that I, CHARLES PARKER, of Meriden, in the county of New Haven, and State of Connecticut, have invented a new Design for Tobacco-Box; and I do hereby declare the following, when taken in connection with the accompanying drawings, and the letters of reference marked thereon, to be a full, clear, and exact description of the same, and which said drawings constitute part of this specification, and represent, in—

Figure 1, a top view; and in

Figure 2, a side view.

This invention relates to a design for a round tobacco-box; and in order to the clear understanding of the same, I will proceed to a full description thereof, as illustrated in the accompanying drawings.

The bottom, or lower part A is struck up from a disk of metal, convex upon its under side, and the top B of similar form, but of less convexity, the two edges, at their meeting, forming a double bead, or oval edge, and around the top, near the edge, I form a raised bead, C, seen in figs. 1 and 2, the bead C forming the distinctive characteristic of this design.

Having fully described my invention, what I claim as new, and desire to secure by Letters Patent, is—
The herein-described design for a round tobacco-box.

CHAS. PARKER.
